VACUUM CONTROLLING MEANS FOR
INTERNAL COMBUSTION ENGINES

William R. Walker, Chicago, Ill.

Application September 16, 1935, Serial No. 40,756

15 Claims. (Cl. 123—119)

My invention consists of means for preventing the development of a relatively and unduly high vacuum or sub-atmospheric pressure, in the intake manifolds of internal combustion engines 5 during decelerating periods of the operation of the engines, without in any way interfering with the development in said manifolds of proper and desired vacua or sub-atmospheric pressures during idling periods, during accelerating periods, 10 and during working periods of said engines.

Heretofore in the operation of internal combustion engines, and particularly where such engines have been used as the motive power for motor-driven vehicles, the degree of vacuum or 15 sub-atmospheric pressure produced in the intake manifolds of such engines at any time has been determined and has resulted from the amount of closure of the throttle valve of the carbureting devices employed and the speed of 20 the engine at that time, regardless of whether the operating conditions then existing, required that degree of vacuum or not. Such carbureting devices when used on motor vehicles, are provided with idling jets for supplying the engines 25 with the small amounts of fuel required to run the engines idle, or at low speed and without load, when the throttle valve is substantially closed and when said idling jets are acted upon by the small amounts of vacuum resulting from 30 such low-speed operation of the engines. With this arrangement, during decelerating periods, particularly of motor vehicles powered with such engines, the throttle valves are substantially closed and the idling jets are subjected to sub- 35 stantial amounts of vacuum due to the relatively high speeds of the engines during the deceleration, with undesirable results, prominent among which are,—first, the drawing into the intake manifold and into the cylinders of the engine, 40 of substantial quantities of fuel, which are neither necessary nor desired, and which cannot be used and are therefore wasted, with the result that the cylinders become flooded or loaded with raw gas producing rough running of the engine 45 when it reaches a subsequent running speed, until it has time to clean itself out; second,—an excessive amount of lubricating oil is sucked past the piston rings and the valve guides by the high degree of vacuum causing waste and smoking 50 from the exhaust pipe; third,—incomplete combustion occurs in the cylinders, resulting in the discharge from the exhaust pipe of foul gases and of a substantial quantity of carbon monoxide; fourth,—firing through the muffler frequently occurs, due to the unburned fuel deliv-

ered to the exhaust pipe; fifth,—the engine runs hotter than it would without the excessive intake vacuum; and sixth,—a substantial drag or retardation is exerted on the vehicle, which frequently is not desired, as evidenced by the special devices heretofore proposed to secure “free-wheeling”.

By my invention, I overcome the undesirable results referred to, by providing control ports for effecting communication to a desired degree, between the interior of the intake manifold and atmosphere, breaking or decreasing the vacuum therein to a desired degree when said ports are open, cooperating with devices for opening and closing said ports, which devices open said ports 15 each time the throttle valve is closed to decelerate the engine, said devices also operating to close said ports each time the idling speed of the engine is reached, and to also close said ports and maintain them closed during each acceleration 20 of the engine and during any and all operating or driving speeds of the engine. The operation of said devices is preferably made automatic, by connecting them with the accelerator mechanism of the engine in such a manner, as 25 described below, that each time said accelerator mechanism is released and moves to its engine idling position, when the engine is running at a speed greater than its idling speed, said ports are thereby opened, and that each time said accelerator mechanism is moved from its idling position to accelerate the speed of the engine, said ports are closed and remain closed until the next movement of the accelerator mechanism to its idling position. Said port controlling de- 30 vices also preferably include speed controlled mechanism for closing said ports, as described below, whereby each movement of the accelerator mechanism to its idling position, opens said ports and begins a decelerating period of the engine, 35 which ends when the decreasing speed reaches the idling speed of the engine, at which time said speed controlled mechanism effects the closing of said ports to establish a proper idling condition for the engine, and all without special 40 thought or act on the part of the operator of the engine.

My invention will be best understood by reference to the accompanying drawings illustrating a preferred embodiment thereof, in which

Fig. 1 shows in side elevation, the assembly of my mechanism between the carburetor and intake manifold of an internal combustion engine,

Fig. 2 is a horizontal, sectional view to an en-

larged scale, of the structure shown in Fig. 1, taken along the line 2—2.

Fig. 3 is a horizontal, sectional view of the structure shown in Fig. 2, taken along the line 5 3—3.

Fig. 4 is a horizontal, sectional view of the structure shown in Fig. 2, taken along the line 4—4, the ports of my mechanism being closed in this figure,

10 Fig. 5 shows in a view similar to Fig. 4, the operating devices of my mechanism in their position for which the ports of said mechanism are open,

Fig. 6 is a horizontal sectional view of a part 15 of the structure shown in Fig. 5, taken along the line 6—6.

Fig. 7 is a horizontal sectional view of a part of the structure shown in Fig. 4, taken along the line 7—7.

20 Fig. 8 shows in a diagrammatic view to an enlarged scale, the quick-break switch illustrated in Fig. 1 as a part of my mechanism,

Fig. 9 is a diagrammatic view of the electrical circuit connections preferably employed in connection with my mechanism illustrated in Fig. 25 1,

Fig. 10 illustrates in a view similar to Fig. 1, a modified form of my mechanism mounted on an intake manifold separately from the carburetor connection with said manifold,

30 Fig. 11 is a diagrammatic detail view of a centrifugal switch of the governor type, for use in electrically controlling my mechanism, instead of the generator relay illustrated in Fig. 9, and

35 Fig. 12 illustrates diagrammatically a type of switch operated by liquid under pressure, which may be employed to electrically control my mechanism, instead of said centrifugal switch and of said generator relay.

Similar numerals refer to similar parts 40 throughout the several views.

As shown in Fig. 1, 10 is a carburetor of the down-draft type, provided with a throttle valve 11, and mounted on the housing 12 of my vacuum controlling mechanism, said mechanism being mounted at its lower end on the intake manifold 13 of an internal combustion engine, not shown. The housing 12 supports a guide 14 for a horizontal rod 15 capable of reciprocating movement in said guide, said rod being pivotally connected at 16 with the lever 17 employed to operate the throttle valve 11 through a link 18 and a plate 19 secured to the outer end of a rod 20 to which said throttle valve is secured. The lever 17 is connected with an operating rod 21, and with a spring 22 to move said lever and the parts connected therewith, to their retracted position to decelerate the engine by closure of the throttle valve 11, when the force exerted on said rod 21 is 50 to drive the engine at a speed greater than its idling speed, is released. A spring 23 connects the lever 17 with the plate 19, to insure closure of the throttle valve 11, when the rod 21 is released.

60 65 The housing 12 comprises heads connected by a tubular body portion 24 on which a sleeve 25 is mounted for angular movement, said sleeve being provided with ports 26, 26 cooperating with similar ports 24a in the body portion 24, in a 70 manner below described. The sleeve 25 is provided with an outwardly extending lug 27 in the path of the rod 15, to which lug a link 28 is connected by a pin 29, the other end of said link being pivotally connected by a pin 30, with the outer end of the core 31 of a solenoid 32. The

link 28 carries a spring actuated pawl 33 for engagement with a notch 15a in the under side of the inner end of the rod 15. The pin 29 is extended above the link 28 to operate a quick-break switch 34 in a manner and for a purpose 5 below described, and the pin 30 extends above the core 31 to engage a light spring detent 35 to releasably hold said core either in its inner or outer position as the case may be, without appreciably interfering with the operating of said core.

The ports in the body portion 24 and in the sleeve 25 are so disposed as to be opened when the lug 27 is moved to the right as seen in Fig. 1, and closed when said lug is moved to the left.

When the lever 17 is moved against the action of the spring 22, to drive the engine faster than idling speed, the rod 15 is moved to the left as far as it will go, which engages the left hand end of

said rod with the lug 27 and moves said lug to its 20 left hand position, at the same time effecting engagement between the pawl 33 and the notch 15a in the rod 15, which lug movement closes the ports in the body portion 24 and in the sleeve 25,

thus operating the engine in the usual manner at 25 all times that the engine is driven above idling speed by operation of the lever 17. When the rod 21 is released and the spring 22 moves the lever 17 to its idling position, the engagement between the pawl 33 and the notch 15a moves the lug 27 30

and the core 31 to the right, opening the ports in the body portion 24 and in the sleeve 25, thereby breaking the vacuum that would otherwise be produced in the manifold 13 during deceleration.

At the end of its movement to the right, the pawl 33 is released from the notch 15a in a manner 35 below described and the vacuum breaking condition referred to, is maintained until the engine decelerates to its idling speed, at which time

devices operated proportionally to engine speed 40 and below described, effect the closure of the operating circuit of the solenoid 32, drawing the core 31 and lug 27 to the left and closing the ports in the body portion 24 and in the sleeve 25.

Movement of the rod 15 to the right, is limited 45 by a pin 15b carried by said rod in a slot 14a in the guide 14, and movement to the left of said rod is limited by jamb nuts 15c on the rod, which nuts then engage the end of the guide 14, said rod having external threads engaging said nuts. The 50 nuts 15c are preferably adjusted so that the rod 15 has free movement in the guide 14 sufficient to move the sleeve 25 from its position closing the vacuum controlling ports to its position opening said ports, or the reverse as the case may be, as a result of which, when the rod 21 is operated to 55 open the throttle valve 11, the rod 15 is moved as far to the left as the nuts 15c will permit, before the throttle valve 11 begins to open, thereby closing said ports, and when the rod 21 is released to permit the spring 22 to move the throttle valve to its idling position, at the time the throttle valve begins to close, the rod 15 is moved by said spring 22, as far to the right as the pin 15b 60 and slot 14a will permit, thereby opening said ports and at the same time releasing the pawl 33 to free the core 31 for operation when the idling speed of the engine is reached, without movement of the lever 17 from its idling position 65 70 when the solenoid 32 is energized.

In Fig. 3 the relation of the body portion 24 to the sleeve 25 is better shown, and in Fig. 2 the relation of the link 28 and pawl 33 to the inner end of the rod 15 is shown, as well as the relation 75

of the ports 24a in the body portion 24, to the ports 26 in the sleeve 25.

In Fig. 4, I illustrate the relation of the operating parts of the sleeve 25, in the position they assume when the ports 24a and 26 are out of alignment with each other, or closed, as shown in Fig. 7, either as a result of movement of the rod 15 to operate the engine faster than its idling speed, or as a result of energization of the solenoid 32. In Fig. 5, I illustrate the position assumed by said operating parts when the ports 24a and 26 are in alignment with each other to break the vacuum in the manifold 13, as shown in Fig. 6, as a result of movement of the rod 15 to the right when the lever 17 is moved to its idling position. It will be noted in Figs. 4 and 5 that the inner lower surface of the guide 14 is beveled to form an inclined cam surface 14b upon which the free end of the pawl 33 rests when in its extreme right hand position, and that, as shown in Fig. 5, when the rod 15 is in its extreme right hand position, the notch 15a is entirely contained within the bore for said rod in the guide 14, thus disengaging the pawl 33 from the rod 15 when movement to the right of the rod 15 has moved the pawl 33 and the sleeve 25 to align the ports 26 with the ports 24a as shown in Fig. 6, in which position the ports remain during the entire time that the lever 17 and the rod 15 remain in their idling position, until the idling speed of the engine is reached, at which time, speed-controlled devices are operated as below described, to energize the solenoid 32 and move the sleeve 25 to the position shown in Fig. 4, moving the ports 26 from alignment with the ports 24a as shown in Fig. 7, and establishing a proper condition for idle running of the engine, as far as connection between the manifold 13 and atmosphere is concerned. Thus movement of the lever 17 to its idling position secures either of two results: first,—where the vehicle is on a level road or upgrade, deceleration of the vehicle occurs, and second,—where the vehicle is on a down grade, coasting will result, and in either case, the effect is similar to "free-wheeling" and without the disadvantages heretofore usually accompanying deceleration. It will be understood that the ports 24a and 26 may have any desired size in any particular case, depending upon the degree to which the undesirable vacuum of deceleration is to be relieved. I find that where there is no relief of the vacuum of deceleration, as has commonly been the case heretofore, it is not unusual to develop during deceleration, a vacuum of from 23 to 25 inches of mercury, whereas the amount of vacuum desirable for idling is about 15 inches of mercury. This substantial difference in vacuum amply accounts for the disadvantages commonly experienced heretofore in connection with deceleration. It will be observed, that where in any special circumstances, it may not be desired to have the advantages of a broken vacuum while the throttle valve is closed, for example, the effect of "free-wheeling" on a down grade, conventional operation of the engine may be had at once, by operating the lever 17 sufficiently to take up its lost-motion, whether the throttle valve is then opened or not, since this small movement of said lever will move the ports 26 out of alignment with the ports 24a, as above described.

As shown in Fig. 8, the switch 34 consists of a base plate 36 of insulating material on which a metal switch blade 37 is pivotally mounted by a stud 38, on which stud an operating plate 39 of

insulating material, is also pivotally mounted. The switch blade 37 carries an electrical contact 40 for electrical connection with a second contact 41 carried by the base plate 36 for one position of said switch blade, and the base plate 36 carries a stop pin 42 against which the switch blade rests for its alternate or open position. A helical spring 43 is connected at its ends with pins 44 and 45 carried respectively by the switch blade 37 and the operating plate 39, which pins are so positioned that the spring extends adjacent to the axis of the stud 38, and on one side or the other of said axis, depending on the position of the operating plate 39. The plate 39 is provided with two spaced pins 46 and 47 which extend outwardly into the path of travel of the pin 29 above described, the spacing of the pins 46 and 47 and the location of the switch 34 on the vacuum controlling mechanism 12, being such that when the link 28 is moved to the right, the switch blade 37 is against its stop pin 42 and the spring 43 holds the pin 47 in engagement with the pin 29, until said movement of the link moves the spring 43 to the right of the stud 38, for which position of the parts, the spring 43 quickly moves the contact 40 into engagement with the contact 41, and at the same time moves the pin 46 into engagement with the pin 29. Similarly, when the link 28 is moved to the left, the pin 29 by its engagement with the pin 46, moves the operating plate to the left until the spring 43 is to the left of the stud 38, for which position of the parts, the spring 43 quickly moves the switch blade 37 against its stop pin 42, and separates the contacts 40 and 41, and at the same time moves the pin 47 into engagement with the pin 29.

In Fig. 9, I illustrate electrical circuit connections that may be used to control the operation of the solenoid 32, as follows. A conventional battery charging generator is illustrated at G, connected with a usual relay R, and through an ammeter A with a storage battery B. The negative brush 48 of the generator is grounded through wire 49; one of the positive brushes, 50, is connected with the field coils 51, 51, the other terminal of which is grounded at 52; the other positive brush 53 is connected by a wire 54 with one terminal of the low resistance winding 55 of the relay R, the other terminal of which winding is connected by a wire 56 with the armature 57 of said relay, and also by a wire 58 with one terminal of the high resistance winding 59 of said relay, the other terminal of the latter winding being grounded at 60. The armature 57 carries a front contact 61 for engagement with a second contact 62 when the relay is energized, said contact 62 being connected by a wire 63 with the ammeter A which in turn is connected by a wire 64 with the positive terminal of battery B, the other terminal of which is grounded at 65. The armature 57 is supported by a flat spring 57a arranged to open the contacts 61 and 62 when the voltage generated by the generator G, decreases by deceleration of the engine driving the generator, to substantially equal the voltage of the battery B, to insure against the discharge of current from the battery through the generator, which condition occurs at or somewhat above the idling speed of the engine.

As the condition of generator voltage last referred to, occurs at substantially the time proper idling conditions of the engine should be established, I make use of the relay R to operate the solenoid 32 as follows. I mount on the armature 57 an insulated back contact 66 connected by a

wire 67 with the contact 41 of the quick-break switch 34, and provide the relay R with a second back contact 68 for engagement by the contact 66 when the armature 57 is in its retracted position. The contact 68 is connected by a wire 69 with the wire 64. The switch blade 37 is connected by a wire 70 with one terminal of the winding of the solenoid 32, the other terminal of which is grounded at 71. As a result of the circuit connections last described, when the engine decelerates to substantially its idling speed and the armature 57 assumes its retracted position moving the contact 66 into engagement with the contact 68, current flows from the battery B through wires 64 and 69, relay contacts 68 and 66, wire 67, switch contacts 41 and 40, switch blade 37, wire 70 to and through the winding of the solenoid 32 and through grounds 71 and 65 back to the battery B. This energizes the solenoid 32 and moves the link 28 to the left, thereby moving the ports 26, 26 from alinement with the ports 24a, 24a, as above described. At substantially the end of this movement, the pin 29 actuates the switch blade 37 and opens the contacts 40 and 41 as above described, to prevent continued current flow from the battery through the solenoid, if the idling condition of the engine is continued for a substantial time interval.

In Fig. 10, I illustrate a modified construction of mechanism for controlling the vacuum in the intake manifold, as follows. In this construction, the carbureter 10 is connected directly with the intake manifold 13a in the usual manner, said carbureter being of the same type, and having a throttle valve 11, operating lever 17, link 18, operating plate 19, valve supporting rod 20, operating rod 21, and springs 22 and 23 as and for the purposes above described. In this case, however, the housing 12a for the vacuum controlling devices, is connected at 13b with the manifold 13a, separately from the carbureter connection therewith, and the operation of controlling the vacuum in said manifold is independent of fluid flow through the carbureter into said manifold. The housing 12a is a metal block having a passageway 72 therethrough, the outer end of said passageway being open to atmosphere and the inner end of said passageway opening directly into the manifold 13a. As a result, when said passageway is unobstructed, air may flow freely through said passageway into said manifold. The housing 12a contains two horizontal and substantially parallel bores crossing said passageway 72 and containing with sliding fits, the rods 73 and 74 respectively. The rod 74 is externally threaded at its right hand portion to carry jamb nuts 75, and at its right hand end it is pivotally connected at 76 with the lever 17. Said rod 74 carries at its left hand end, a flange 77 limiting movement of said rod to the right, for which position a portion of said rod of reduced diameter forming a circumferential port 74a around said rod, is in line with the passageway 72. The nuts 75 are adjusted on the rod 74 to permit said rod to move sufficiently to the left to remove the port 74a from alinement with the passageway 72, the body portion of said rod being large enough to then completely close said passageway. The relation of the nuts 75 to the flange 77, provides an amount of lost motion for the pivotal connection 76, corresponding with the lost motion of the pivotal connection 16 above described, so that for any movement of the lever 17 in Fig. 10 from its decelerating or released position, the passageway 72 is closed by the rod 74 just before the throttle

valve 11 is opened, and for any movement of the lever 17 to its decelerating position, the port 74a is moved into alinement with the passageway 72 just before the throttle valve 11 is closed.

The rod 73 is a part or extension of the core 5 of the solenoid 32 supported by the housing 12a in line with said rod, and said rod 73 is provided with a circumferential port 73a similar to the port 74a, which port 73a is in line with the passageway 72 when the solenoid core is in its outer 10 position, and is out of alinement with said passageway when said solenoid is energized and said rod 73 is moved to its right hand position, said rod having on its left hand end, a flange 78 which limits movement of the rod 73 to the right, by 15 engagement of the flange 78 with the flange 77. The body portion of the rod 73 is large enough to completely close the passageway 72, and said rod carries a pin 29a extending through a clearance slot 12b therefor in the housing 12a, to operate a quick-break switch 34 in the same manner and for the purpose above described in connection with the operation of a like switch by the pin 29. A light spring detent 79 carried by the housing 12a, engages the edge of the flange 78 25 to yieldingly hold the rod 73 in either its right hand or its left hand position, without appreciably interfering with moving said rod to its other position. The flanges 77 and 78 overlap each other, so that movement of the rod 74 to its 30 left hand position, also, through said flanges, moves the rod 73 to its left hand position. The construction described, results in closing the passageway 72 by the rod 74, for all positions of the lever 17 excepting its decelerating position, and in opening said passageway at the port 73a for all 35 running conditions of the engine substantially above its idling speed; it also provides for closing said passageway 72 by the rod 73 by the action of speed controlled devices, at substantially the time 40 the engine reaches its idling speed, since the circuit connections and speed controlling devices described above in connection with Fig. 9, apply in the same manner to the controlling of the solenoid 32 in Fig. 10 as they do to the controlling 45 of the solenoid 32 in Fig. 1, and with substantially the same results. The passageway 72 and the ports 73a and 74a may be proportioned as desired, to secure any desired amounts of vacuum reduction during deceleration, in different cases. 50

In Fig. 11, I illustrate a different type of speed controlled devices for closing the circuit of the solenoid 32, as follows. The engine shown diagrammatically at 80, has a pulley 81 on its crank shaft 82, driving by means of a belt 83, a pulley 84 on a stud shaft 85 which pulley 84 carries a disk 86 which in turn carries an insulated contact ring 87 on which a brush 88 carried by and insulated from the engine frame, bears. The disk 86 carries an insulated stud 89 on which a 60 contact arm 90 is mounted for angular movement, said arm being electrically connected by a wire 91 with the ring 87. The arm 90 carries a first contact 92 for engagement with a second contact 93 carried by the disk 86 and in electrical connection with the frame of the engine, by movement of said arm inwardly towards the axis of the ring 87. The movable end of the arm 90 is connected with one end of a helical spring 94, the other end of which spring is connected by 70 means of a flexible wire or cord 95 with an adjusting stud 96 carried by the disk 86, rotation of said stud 96 in said disk, serving to change the tension on said spring 94 as desired. The positive terminal of the battery B is connected 75

by a wire 97 with the contact 41 of the switch 34, the switch blade 37 of which switch is connected by a wire 98 with one terminal of the winding of the solenoid 32, the other terminal of which is connected by a wire 99 with the brush 88. The negative terminal of the battery B is grounded as at 100, and the engine frame is grounded as at 101. As a result of the structure and circuit connections last described, with the spring 94 adjusted to close the contacts 92 and 93 when substantially idling speed of the engine 80 is reached, all higher speeds of the engine will hold the contacts 92 and 93 in open condition, and the closed condition of said contacts will be effected only when the engine is decelerated to substantially its idling speed, which closes the energizing circuit of the solenoid 32 from the battery B through the wire 97, contacts 41 and 40, switch blade 37, wire 98, winding of solenoid 32, wire 99, brush 88, ring 87, wire 91, contact arm 90, contacts 92 and 93 to the engine frame, and thence by grounds 101 and 100 back to battery B. The speed actuated circuit controlling devices illustrated in Fig. 11, secure the same result as secured for my vacuum controlling mechanism by the generator and relay construction illustrated in Fig. 9, and they are applicable to the vacuum controlling mechanism shown either in Fig. 1 or Fig. 10 or their equivalents, to secure the same results as those above described.

In Fig. 12, I illustrated a still different form of speed controlled devices for closing the circuit of the solenoid 32, as follows. The engine shown diagrammatically at 105, carries a pulley 106 on its crankshaft 107, which, by means of a belt 108, drives a pump 109 having an intake pipe 110 and a discharge pipe 111 extending to the engine 105 to control the circulation of desired liquid, for example, cooling water or lubricating oil, to and through the engine. The high pressure pipe 111 is connected by a branch pipe 112 with a liquid compartment 113 having its top closed by a corrugated diaphragm 114, preferably of spring metal. A stud 115 of insulating material, rests on top of the central portion of the diaphragm 114, to support the outer end of an insulated contact arm 116 carrying a contact 117 for engagement with a second insulated contact 118 having a fixed support, when the position of the diaphragm permits such engagement. A spring arm 119 having a fixed support at one end, carries at its other end an adjusting screw 120 pressing upon the outer end of the contact arm 116, to regulate as desired, the liquid pressure in the compartment 113, for which the spring arm 119 will move the contact 117 into engagement with the contact 118. The positive terminal of the battery B is connected by a wire 121 with the contact arm 116; the contact 118 is connected by a wire 122 with the contact 41 of switch 34; the switch arm 37 is connected by a wire 123 with one terminal of the winding of the solenoid 32, the other terminal of which is grounded at 124; and the negative terminal of the battery B is grounded at 125.

As a result of the construction and circuit connections last described, with the screw 120 adjusted to close the contacts 117 and 118 when substantially idling speed of the engine 105 is reached, all higher speeds of the engine will hold the contacts 117 and 118 in open condition, since the liquid pressure then developed by the pump 109 and exerted upon the diaphragm 114 and in turn exerted by the stud 115 upwardly on the contact arm 116, is greater than the downward

force exerted by the spring arm 119 through the screw 120 on said contact arm 116 when the said contacts are closed. When the engine is decelerated to substantially its idling speed, the liquid pressure on the diaphragm 114 is sufficiently reduced to permit the spring arm 119 to move the contact 117 into engagement with the contact 118, closing the energizing circuit of the solenoid 32 from the battery B through the wire 121, contact arm 116 and contacts 117 and 118, wire 122, contacts 41 and 40, switch blade 37, wire 123, winding of the solenoid 32, and through grounds 124 and 125 back to battery B. The speed actuated circuit controlling devices illustrated in Fig. 12, operate my vacuum controlling mechanism in the same manner as the generator relay and as the centrifugal switch above described and with the same results, and they are applicable to the vacuum controlling mechanism shown either in Fig. 1 or Fig. 10 or their equivalents, to secure the same results as those above described.

In carrying out my invention the requisites are first,—that air shall be admitted to the intake manifold of the engine during its periods of deceleration, to decrease or break the vacuum to the desired degree, whether by the specific means described or by equivalent means, and preferably by the operation of the usual speed controlling mechanism of the engine, without so admitting the air during power delivering periods of the operation of the engine, and second,—that the said admission of air shall be stopped and prevented when the engine is idling, whether by the specific means described or by equivalent means operated preferably by the engine directly or indirectly, and at the speed thereof or proportionally thereto, to the end that in its preferred embodiment, my said invention may be automatic in operation and require no thought or attention on the part of the operator of the engine.

I do not, therefore, in carrying out my invention, limit myself to the particular construction shown and described, as I may employ equivalents thereof known to the art at the time of the filing of this application, without departing from the scope of the appended claims.

What I claim is:

1. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alignment with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed.

2. In a device of the class described, the com-

bination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said body portion comprising a tubular member connecting the mixture delivering opening of said carbureting mechanism with said manifold, and said first member comprising a sleeve fitting and movable angularly on said tubular member, said tubular member and said sleeve having cooperating ports therethrough establishing said open and closed positions of said first member.

3. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said second member comprising a ported rod crossing said passageway and movable longitudinally to its passageway opening and closing positions.

4. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said body portion comprising a tubular member connecting the mixture delivering opening of said carbureting mechanism with said manifold, and said first member comprising a sleeve fitting and movable angularly on said tubular member, said tubular member and said sleeve having cooperating ports therethrough establishing said open and closed positions of said first member.

position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said members comprising two ported rods each crossing said passageway and each movable longitudinally to its passageway opening and closing positions.

5. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said members comprising first and second ported rods each crossing said passageway and each movable longitudinally to its passageway opening and closing positions, said rods having interengaging extensions moving said second rod to its passageway opening position by movement of said first rod to its passageway closing position, and leaving said second rod in its passageway opening position for movement of said first rod to its passageway opening position, energization of said solenoid moving said second rod to its passageway closing position.

6. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected with said first member and by energization of the solenoid moving the port of said first member to close said passageway, and a speed controlled switch in circuit with said solenoid winding and closing said circuit for the idling speed of the engine, said switch opening said circuit for speeds of the engine greater than its idling speed, said body portion comprising a tubular member connecting the mixture delivering opening of said carbureting mechanism with said manifold, and said first member comprising a sleeve fitting and movable angularly on said tubular member, said tubular member and said sleeve having cooperating ports therethrough establishing said open and closed positions of said first member.

cuit for speeds of the engine greater than its idling speed, said cooperating devices comprising a lug extending from said first member, a link connecting said lug with the core of said solenoid, 5 a rod in line with said link for abutting engagement therewith and connected with said second member, a pawl carried by said link for engagement with said rod to retract said core by longitudinal movement of said rod, and a cam for 10 disengaging said pawl at the end of retracting movement of said core.

7. In a device of the class described, the combination of an intake manifold of an internal combustion engine, carbureting mechanism including a throttle valve for supplying fuel mixture to said manifold, mechanism for supplying air to said manifold and including a body portion having a passageway in communication with the interior of said manifold and atmosphere, a first 15 movable member having a port for alinement with said passageway for its open position, a second member connected with said throttle valve and movable to power producing and idling positions respectively opening and closing said throttle valve, cooperating devices between said members and moving the port of said first member to open position by movement of said second member to its idling position, a solenoid having an energizing winding and having a core connected 20 with said first member and by energization of the solenoid moving the port of said first member to close said passageway, and a speed controlled switch in circuit with said solenoid winding and closing said circuit for the idling speed of the 25 engine, said switch opening said circuit for speeds of the engine greater than its idling speed, said body portion comprising a tubular member connecting the mixture delivering opening of said carbureting mechanism with said manifold, and said first member comprising a sleeve fitting and 30 movable angularly on said tubular member, said tubular member and said sleeve having cooperating ports therethrough establishing said open and closed positions of said first member, said cooperating devices comprising a lug extending 35 from said sleeve, a link connecting said lug with the core of said solenoid, a rod in line with said link for abutting engagement therewith and connected with said second member, a pawl carried by said link for engagement with said rod to retract said core by longitudinal movement of said rod, and a cam for disengaging said pawl at the 40 end of retracting movement of said core.

8. Means for controlling the vacuum in the intake manifold of an internal combustion engine provided with carbureting mechanism having a throttle valve movable to power producing and idling positions, consisting of the combination of a body portion for connection with an intake manifold and having a passageway for open communication with the interior of said manifold, movable valve mechanism having ports controlling opening and closing said passageway to atmosphere, a member for connecting said valve mechanism with the throttle valve of the engine, whereby movement of said throttle valve to its idling position moves said valve mechanism to its open position, and electro-magnetic mechanism connected with said valve mechanism and by its actuation moving said valve mechanism to its closed position.

9. Means for controlling the vacuum in the intake manifold of an internal combustion engine provided with carbureting mechanism having a throttle valve movable to power producing

and idling positions, consisting of the combination of a body portion for connection with an intake manifold and having a passageway for open communication with the interior of said manifold, movable valve mechanism having ports controlling opening and closing said passageway to atmosphere, a member for connecting said valve mechanism with the throttle valve of the engine, whereby movement of said throttle valve to its idling position moves said valve mechanism to its open position, and electro-magnetic mechanism connected with said valve mechanism and by its actuation moving said valve mechanism to its closed position, said body portion comprising a tubular member connecting the mixture delivering opening of said carbureting mechanism with said manifold, and said valve mechanism comprising a sleeve fitting and movable angularly on said tubular member, said tubular member and said sleeve having cooperating ports therethrough establishing said open and closed positions of said valve mechanism.

10. Means for controlling the vacuum in the intake manifold of an internal combustion engine provided with carbureting mechanism having a throttle valve movable to power producing and idling positions, consisting of the combination of a body portion for connection with an intake manifold and having a passageway for open communication with the interior of said manifold, movable valve mechanism having ports controlling opening and closing said passageway to atmosphere, a member for connecting said valve mechanism with the throttle valve of the engine, whereby movement of said throttle valve to its idling position moves said valve mechanism to its open position, and electromagnetic mechanism connected with said valve mechanism and by its actuation moving said valve mechanism to its closed position, said valve mechanism comprising a ported rod crossing said passageway and movable longitudinally to its passageway opening and closing positions.

11. Means for controlling the vacuum in the intake manifold of an internal combustion engine provided with carbureting mechanism having a throttle valve movable to power producing and idling positions, consisting of the combination of a body portion for connection with an intake manifold and having a passageway for open communication with the interior of said manifold, movable valve mechanism having ports controlling opening and closing said passageway to atmosphere, a member for connecting said valve mechanism with the throttle valve of the engine, whereby movement of said throttle valve to its idling position moves said valve mechanism to its open position, and electro-magnetic mechanism connected with said valve mechanism and by its actuation moving said valve mechanism to its closed position, said valve mechanism comprising two ported rods each crossing said passageway and each movable longitudinally to its passageway opening and closing positions, said rods having connection with said throttle valve and said electromagnetic mechanism respectively for operation thereby.

12. Means for controlling the vacuum in the intake manifold of an internal combustion engine provided with a throttle valve having power producing and idling positions, consisting of the combination of a body portion for connection with an intake manifold and having a passageway for air flow into said manifold, a ported member for mechanical connection with the throttle valve of

the engine and mechanically opening said passageway by movement of said throttle valve to its idling position, and devices operated proportionally to the speed of the engine and closing said 5 passageway for the idling speed of the engine.

13. Means for controlling the vacuum in the intake manifold of an internal combustion engine provided with a throttle valve having power producing and idling positions, consisting of the combination of a body portion for connection with an 10 intake manifold and having a passageway for air flow into said manifold, a ported member for mechanical connection with the throttle valve of the engine and mechanically opening said passageway by movement of said throttle valve to its 15 idling position, and devices operated proportionally to the speed of the engine and closing said passageway for the idling speed of the engine, said devices including electromagnetic mechanism 20 and a speed controlled switch controlling the operation of said electromagnetic magnetism.

14. Means for controlling the vacuum in the intake manifold of an internal combustion engine provided with a throttle valve having power producing and idling positions, consisting of the combination of a body portion for connection with 25

an intake manifold and having a passageway for air flow into said manifold, a ported member for mechanical connection with the throttle valve of the engine and mechanically opening said passageway by movement of said throttle valve to its 5 idling position, and devices operated proportionally to the speed of the engine and closing said passageway for the idling speed of the engine, said ported member also mechanically closing said passageway for power producing positions of said 10 member.

15. Means for controlling the vacuum in the intake manifold of an internal combustion engine provided with a throttle valve having power producing and idling positions, consisting of the combination of a body portion for connection with an intake manifold and having a passageway for air flow into said manifold, valve mechanism for opening said passageway and mechanically actuated by a rod mechanically connected with the 15 throttle valve by movement to its idling position of the throttle valve, and devices connected with said valve mechanism and driven by said engine and effecting the closure of said passageway for the idling speed of said engine. 20

25 WILLIAM R. WALKER.
